Patented Mar. 5, 1918.

UNITED STATES PATENT OFFICE.

JOHN W. COAST, JR., OF TULSA, OKLAHOMA, ASSIGNOR TO THE PROCESS COMPANY, A CORPORATION OF MARYLAND.

MEANS FOR CRACKING HYDROCARBONS.

1,258,191.

Specification of Letters Patent.

Patented Mar. 5, 1918.

Application filed March 22, 1917. Serial No. 156,650.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in Means for Cracking Hydrocarbons, of which the following is a full, clear, and exact description, reference being had to the accompanying drawing, forming a part of this specification.

My invention relates to improvements in apparatus for cracking hydrocarbons, and more particularly to means for protecting 15 stills from the injurious effects of coke or tarry coke-forming substances.

When high boiling point petroleum hydrocarbons are vaporized and cracked in the ordinary cylindrical still, heavy coke-forming substances settle to the bottom of the 20 liquid in the still. If the coke or carbon is permitted to collect on the still bottom, it will prevent the free transmission of heat to the liquid contents of the still, and when 25 a sufficient quantity has accumulated, the still bottom will become red hot. Some immediate steps must then be taken to avoid a rupture at the overheated portion of the still. In actual practice, the coke accumulates on the hot still bottom when oil in the 30 still is maintained at a high temperature and under a high pressure, thus rendering the cracking operation quite dangerous. On account of the danger, and for economic reasons, 35 the coke is usually removed from the still at frequent intervals.

The main object of my invention is to prevent the coke, or tarry coke-forming substances from accumulating on the still bottom where the heat is transmitted to the 40 still. In the preferred form of the invention, this is accomplished by maintaining a body of heavy liquid in the bottom of the still, floating the oil to be distilled on said 45 heavy liquid and transmitting heat through the heavy liquid to vaporize the floating liquid. The heavy liquid, preferably molten metal, interposed between the still bottom and the oil, prevents the coke-forming substance 50 from reaching the bottom of the still. Since the heat cannot be transmitted readily through the coke or carbon, the latter is preferably circulated or skimmed along the surface of the heavy liquid to the 55 end portions of the still. By preventing the

coke from accumulating on the still bottom, the cracking operation may be carried out continuously for a considerable period of time, without cleaning the interior of the still. Furthermore, the still bottom will 60 not be overheated by the temperature to which it is ordinarily subjected.

Figure I is a diagrammatical view of a cracking apparatus, embodying the features 65 of my invention.

Fig. II is a transverse section of the still taken on the line II—II, Fig. I.

Fig. III is a detail view of the filler whereby the heavy liquid is displaced to contact with a greater area of the still bottom.

The still 1, arranged above a heating chamber 2, is connected by means of an air cooled vapor pipe 3 to a reflux condenser 4. 5 designates a vapor pipe leading from the reflux condenser to a main condensing coil 6 from which the low boiling point product is recovered. The condensing coil 6 is preferably arranged in a water tank 7. The air cooled vapor pipe 3 constitutes a reflux condenser, and it is inclined to allow the condensate to flow backwardly to the still.

The apparatus I have shown is particularly adapted for use in cracking high boiling point products of distillation, such, for 85 example, as the distillates or residues resulting from the distillation of the crude petroleum. The substances to be treated are introduced into the still in any suitable manner, and any desired pressure may be 90 obtained by regulating a valve 8, preferably located in the vapor pipe 5. The pressure in the still is preferably greater than fifty pounds per square inch, and the temperature of the contents of the still preferably ranges 95 from about 600° F. to 800° F. The low boiling point vapors passing from the liquid, flow through the vapor pipe 3 and reflux condenser 4 to the pipe 5, leading to the main condenser 6. The relatively high boiling point fractions are condensed in the vapor pipe 3 or in the condenser 4, such fractions being returned to the still through the inclined vapor pipe 3. This reflux condensate includes a large percentage of heavy 100 coke-forming fractions, commingled with lighter fractions, which may be redistilled to form part of the low boiling point product.

In the preferred form of the invention, 110

the end portions of the still bottom are seated upon the walls 9 of the heating chamber, and these walls protect said end portions from the intense heat of the heating chamber. The heat is transmitted directly through the middle portion of the still bottom, and the protected end portions of the still are maintained in a relatively cool condition.

10 A body of heavy liquid 10, preferably a readily fusible metal, for example, molten lead, is maintained in the bottom of the still. The oil to be distilled floats upon the surface of the molten lead 10, and the heavy coke-forming fractions which drop by gravity to the bottom of the oil, also float upon the lead. The molten lead thus prevents the coke-forming substance from reaching the hot still bottom. The heat is transmitted 20 from the still bottom, through the molten lead, to the floating oil. Owing to the high temperature, the lead is circulated and agitated so as to very effectively transmit the heat to the oil.

25 The coke is not a good conductor of heat, and it is, therefore, circulated along the surface of the lead to points directly above the walls 9, where it will not materially interfere with the transmission of heat from the 30 heating chamber to the oil.

The means for circulating or skimming the coke comprises a skimmer 11 fitted to a rotary feed screw 12 which extends through a stuffing box 13 at one end of the still. 35 Gearing 12' may be operated in any suitable manner to rotate the feed screw 12. This feed screw is reversible, so that it may be actuated to reciprocate the skimmer 11 from one end portion of the still to the other. 40 Stationary rods 14 prevent the skimmer 11 from turning on the feed screw 12. The lower portion of the skimmer extends entirely across the lower portion of the still, and it also extends into the molten lead 10. 45 By confining the oil and molten lead, as herein shown and described, I prevent the vapors generated in the still from passing into, or bubbling through the molten lead. The vapors are discharged from the upper 50 portion of the still at a point above the oil.

15 designates a filling device, in the form of a coil of pipe, submerged in the molten lead to avoid the use of an extremely large quantity of lead. This filling device 15 55 places some of the lead, causing it to protect a greater area of the still. The coil of pipe constituting the filling device is capped

at its ends, as shown at 16 in Fig. III, to prevent the lead from entering the pipe. Anchors 17, secured to the bottom of the 60 still, prevent the hollow filling device 15 from floating on the surface of the molten lead.

I claim:

1. A cracking still provided with a body 65 of heavy fusible material on its bottom wall, a heating chamber below said bottom wall, and means for moving coke-forming substance along the surface of said heavy fusible material.

2. A cracking still provided with a body 70 of heavy liquid forming a support for the liquid to be distilled, and a skimmer arranged to move coke-forming substance along the surface of said heavy liquid.

75 3. A cracking still provided with a body of heavy liquid forming a support for the liquid to be distilled, a skimmer arranged partly within said heavy liquid, and means for reciprocating said skimmer to move 80 coke-forming substance along the surface of said heavy liquid.

4. A cracking still provided with a body 85 of heavy liquid forming a support for the liquid to be distilled, a skimmer arranged partly within said heavy liquid, and means for reciprocating said skimmer to move coke-forming substance along the surface of said heavy liquid, said means including a reversible feed screw fitted to said skimmer. 90

5. A cracking still provided with a body 95 of molten lead forming a support for the liquid to be distilled, a skimmer extending into said molten lead, and a reversible feed screw for reciprocating said skimmer to float coke forming substance along the surface of said molten lead and to the end portions of the still.

6. In a distilling apparatus, a cracking still, a heating chamber below said still, the end walls of said heating chamber being directly below the end portions of the still bottom, a body of heavy fusible material arranged in the still and forming a support for the liquid to be distilled, said fusible material being so heavy that the coke-forming substance will float on its surface, and a skimming device forcing such coke forming substance to a point directly above one of the end walls of said heating chamber. 100 105

In testimony that I claim the foregoing I hereunto affix my signature.

JOHN W. COAST, JR.
